UNITED STATES PATENT OFFICE.

LEWIS L. LIBBY, OF WINDSOR LOCKS, CONNECTICUT.

TRANSMISSION-BAND LINING.

1,357,103.

Specification of Letters Patent. Patented Oct. 26, 1920.

Application filed August 2, 1919. Serial No. 315,018.

To all whom it may concern:

Be it known that I, LEWIS L. LIBBY, a citizen of the United States, residing at Windsor Locks, in the county of Hartford 5 and State of Connecticut, have invented new and useful Improvements in Transmission-Band Linings, of which the following is a specification.

The object of my present invention is the provision of a simple, easily applied and efficient transmission band lining designed more particularly for use in conjunction with the bands and the drums of a Ford transmission, so that the compression of any 10 one of the bands will be attended by the creation of adequate friction between the unitary lining and the drum complementary to said band, and this without the unitary lining affecting the other drum.

20 To the attainment of the foregoing the invention consists in the novel transmission band lining and in the combination herein-after described and definitely claimed.

In the accompanying drawings, hereby 25 made a part hereof:

Figure 1 is a perspective of my novel transmission band lining, *per se*.

Figs. 2 and 3 are views showing the arrangement of my novel band relatively to 30 the drums and plural bands of a Ford transmission.

Similar numerals of reference designate corresponding parts in all of the views of the drawings:

35 The transmission illustrated is of the well known Ford type, and it is therefore unnecessary to describe the same, except to say that it comprises a casing 1, the brake drum 2, the low speed drum 3, the reverse drum 40 4, and the bands 2^a, 3^a and 4^a, complementary to the drums 2, 3 and 4, respectively, and designed to be operated in the ordinary well known manner.

45 My novel unitary band lining 5 is preferably, though not necessarily, formed of textile material, and it is peculiar in that it is of a width equal to the combined width of the plurality of drums 2, 3 and 4. At one end the lining 5 is bifurcated, as indicated 50 by 6, to form the two tabs 7, in which are eyelets 8, preferably of brass. These eyelets 8 are designed for the reception of the shafts of the speed levers, and they serve to prevent premature wear of the lining 5.

55 In order to apply my novel lining 5, it

is simply necessary to slip the same into working position between the perimeters of the drums 2, 3 and 4, and the inner surfaces of the transmission band complementary to said drums, and to arrange the eyelet-bearing end of the lining 5, as described, relatively to the speed lever shafts. Manifestly the lining 5 may be expeditiously and easily applied in the manner stated, without disarranging the transmission bands and without the necessity of removing the top of the transmission casing.

In the practical use of my novel unitary band lining, it will be readily understood that the conventional contraction of any one 70 of the bands 2^a, 3^a or 4^a will enable the lining 5 to adequately hold against turning the drum of the contracted band, and this without affecting the other drums, notwithstanding the interposition of the single lining 5 between the several drums and their transmission bands.

Having described my invention, what I claim and desire to secure by Letters-Patent, 80 is:

1. As a new article of manufacture, a transmission band lining of a width equal to the combined widths of the drums of a Ford transmission and equipped at one end with means for connection to the speed lever 85 shafts of said transmission; the said lining being adapted to be slipped into position between the perimeters of the drums and their complementary bands.

2. As a new article of manufacture, a 90 transmission band lining of a width equal to the combined widths of the drums of a Ford transmission and bifurcated at one end to provide spaced tabs and equipped in said tabs with eyelets for the reception of the 95 speed lever shafts of the transmission; the said lining being adapted to be slipped into position between the perimeters of the drums and their complementary bands.

3. The combination with the drums and 100 bands of a transmission, of a band lining of a width for interposition between the several drums and the bands thereof; said lining being interposed between the several drums and bands and being connected at 105 one end with the speed lever shafts of the transmission.

4. As a new article of manufacture, a transmission band lining of a width equal to the combined widths of the drums of a Ford 110

transmission and equipped at one end with means for fastening it in working position; the said lining being adapted to be slipped into position between the perimeters of the 5 drums and their complementary bands.

5. The combination with the drums and bands of a transmission, of a band lining of a width for interposition between the several drums and the bands thereof; said 10 lining being interposed between the sev-

eral drums and bands and being fastened at one end.

6. Automobile transmission mechanism involving a series of drums arranged side by side, a strap around each drum, means for 15 individually constricting each strap around its coöperating drum, and a single band between the drums and the straps.

In testimony whereof I affix my signature.
LEWIS L. LIBBY.
